UNITED STATES PATENT OFFICE.

CHARLES E. TEMPLE AND FRANK T. BOLTON, OF TERRE HAUTE, INDIANA.

BUTTON-SETTING MACHINE.

SPECIFICATION forming part of Letters Patent No. 392,647, dated November 13, 1888.

Application filed February 8, 1887. Serial No. 226,971. (No model.)

To all whom it may concern:

Be it known that we, CHARLES E. TEMPLE and FRANK T. BOLTON, citizens of the United States, residing at Terre Haute, in the county 5 of Vigo and State of Indiana, have invented a new and useful Improvement in Button-Setting Machines, of which the following is a specification.

Our invention relates to machines for setting buttons; and it consists of the peculiar combination of devices and novel construction and arrangement of the various parts for service, substantially as hereinafter fully described, and particularly pointed out in the claims.

Among other things our invention has for 15 its object to provide a button-setting machine with an endwise-moving die, which is held perfectly true in its movements, to insure the proper and effective clinching of the button- 20 fastener; to provide an improved rotary carrier, which is arranged to move in a vertical plane, and with a step-by-step movement to automatically and properly adjust the buttons carried thereby to the die; and, further, to 25 provide mechanism of simple construction for automatically moving or feeding the carriage one step on each retrograde movement of the die; and, finally, the object of our invention is to provide an improved button-setting 30 machine which shall possess superior advantages over others of its class which have preceded it, in points of simplicity, strength, and durability of construction, ease and efficiency of operation, and cheapness of manufacture.

In the accompanying drawings, Figure 1 is 35 an elevation taken from one side of a button-setting machine embodying our invention. Fig. 2 is a front view thereof. Fig. 3 is an enlarged perspective view of that portion of 40 our machine above the table. Fig. 4 is a vertical sectional view on the line $x-x$ of Fig. 2, but on an enlarged scale. Fig. 5 is a transverse horizontal sectional view on the line $X-X$ of Fig. 4, to illustrate the manner in which 45 the switch operates to move or feed the carrier; and Fig. 6 is a detached detail view of the support looking at the front side thereof, to more clearly show the grooves or channels and the switch.

Referring to the drawings, in which like 50 letters of reference denote corresponding parts

in all the figures, A designates the table of our improved button - setting machine, which is supported rigidly in place upon a suitable standard, a , to the lower end of which are 55 rigidly secured the diverging legs a' . We do not, however, desire to confine ourselves to any specific form of table or frame, as we are aware that the same can be very widely varied. Upon this horizontal table A is rigidly affixed, 60 in any suitable manner, a vertically-disposed standard, B, and the vertical rotary carrier or magazine C is journaled or hung upon a suitable shaft, c , in the upper extremity of the standard. This standard B has an enlarged 65 base, b , one end of which extends or projects beyond the standard proper, as at b' , so that the vertical carrier lies above or overhangs the same, for a purpose presently described. The base b has a longitudinal slot or recess, d , 70 formed in the lower part thereof; but this slot or recess does not extend the entire length of the base, and the free projected end b' of the base has a vertical opening, d' , formed therein. In this vertical opening of the base is fitted 75 the vertically-movable die D, which is guided in its sliding movements and held from rotary movement by any preferable means—as, for instance, a feather and groove, as clearly shown.

The horizontal table A has a slot, a^2 , which aligns with the slot d of the base, and in these slots works a horizontal lever, E, which is hung or suspended at an intermediate point of its length, as at e . One end of this lever is 80 adapted to operate the vertically-movable die D, to impel the same against the carrier, and the opposite end of this horizontal lever is 85 connected with a foot-treadle, E', by an intermediate rod, e^2 . The lever may be connected 90 with the movable die, or it may rest or bear against the same, and the downward movement of the die is limited by the lever, which is held in place by the treadle, that is in turn controlled by a spring, E². This treadle is 95 preferably hung at an intermediate point of its length from one of the diverging feet a' , and the spring is connected at one end to the treadle and at the other end to the standard or one of the legs. The free end of the treadle 100 is normally held in an elevated position by the spring, and the die is thereby normally

depressed, so that upon a single downward movement of the treadle the die is elevated, and when the pressure on the treadle is released the latter and die are returned automatically to their normal positions, to be in condition for immediate use. We do not, however, desire to claim or confine ourselves to the specific device for operating the die, as the same is described in a prior patent, No. 10 345,740, issued to us on the 20th day of July, 1886.

The vertical rotary carrier is provided with a broad annulus or flange, F, which may be formed or cast integral therewith, or it can be made separate from the carrier and detachably secured thereto by suitable devices, as in our prior patent hereinbefore referred to. This annulus projects or extends beyond one of the vertical faces of the carrier, and in this edge 15 are formed open slots f, which receive the shanks of the fasteners, while the buttons lie within or rest upon the inner sides of the flange.

The annular flange F of the carrier or magazine projects at right angles from the body 20 thereof, and the buttons and connected fasteners are fitted in the slots of the flange, upon which the die acts to force the fastener through and clinch the same on the leather, the flange thus serving as an anvil, as set forth.

The upper end of the endwise-moving die 25 is reduced, as at g, and on the upper extremity of this reduced neck g is formed or secured the head D' of the die, the upper face of which may have suitable grooves or channels formed 30 therein for the reception and proper clinching of the button-fastener.

H designates a support which is fitted around the reduced neck of the die and beneath the head thereof, so that it is rigidly held or fixed 35 in place thereon. This support is carried by the die in its vertical movements, and it carries mechanism for automatically feeding the carrier one step upon the retrograde movement of the die, to properly adjust the succeeding 40 button and its fastener in position to be operated upon by the die. This support is provided with a vertical arm, I, which is arranged out of line with the carrier. One face of the support is arranged in close proximity to or 45 actual contact with the inner face of the carrier, and on this face of the support is formed a groove or channel, J, to be more fully described presently. The inner face of the carrier has a series of pins or studs, i, projecting 50 outwardly toward the support, which are adapted to successively enter the channel J and be acted on by an automatic switch, K, which operates to feed or move the carrier with a step-by-step movement. The channel 55 or groove J of the support is provided with an enlarged upper portion, and one side thereof is curved, as at j, so that when the support is depressed this curved side of the channel thereof will act in conjunction with the switch upon 60 the pin or stud i to expel the same from the straight part of the channel and thereby feed the carrier.

The switch is provided with the curved sides k k' and tapered to a point, and it is pivoted at its upper end to the support, as at L'. The free tapered end of this switch is arranged between the entrance and exit points of the channel, and it is normally pressed against the straight side of the channel by a spring, K'. 70

It will be seen that the die is arranged in 75 line with the carrier and that it acts against the periphery of the same.

Although we have shown and described the carrier and die arranged in vertical planes, still it is obvious that they can be disposed in 80 horizontal planes without departing from the spirit of our invention.

This being the construction of our improved button-setting machine, the operation thereof is as follows: The buttons and their fasteners 85 are first placed properly in the carrier, after which it is adjusted so that one of the pins thereof impinges against the side k of the automatic switch. The work to which the button is to be fixed is held beneath the carrier, and 90 pressure applied to the treadle to impel the die against the work and the latter against the carrier, so that the fastener is forced through the work. The support is carried upwardly with the die, so that the pin of the carrier will 95 press the yielding switch to one side, and thereby permit the pin to enter the groove beneath the switch, and when the spring E' returns the treadle and die to their normal positions the support is forced downwardly 100 and the pin rides between the curved edges j k' of the support and switch, which thereby serves to feed or move the carrier one step forward.

Having thus fully described our invention, 105 what we claim as new, and desire to secure by Letters Patent, is—

1. In a button-setting machine, a pivoted button magazine or carrier, comprising a disk having an annular flange at an angle to its body, said flange being slotted for the reception of buttons and connected fasteners, and serving as an anvil, substantially as described, for the purpose set forth.

2. In a button-setting machine, a magazine 115 or carrier comprising a disk pivoted to a standard and having an annular flange, said flange being slotted for the reception of buttons and connected fasteners, in combination with a die operating against the flange, and mechanism for feeding the carrier or magazine, substantially as described, for the purpose set forth.

3. In a button-setting machine, a centrally pivoted magazine or carrier having an annular flange extending at right angles to the body and slotted for the reception of buttons and connected fasteners, in combination with a sliding die arranged to act against the flange, and mechanism carried by the die for moving the carrier with a step-by-step motion, substantially as described, for the purpose set forth.

4. In a button-setting machine, the combination of a rotatable carrier, an endwise-mov-

ing die, and an automatic switch for moving or feeding the carrier a predetermined distance upon each retrograde movement of the die, substantially as and for the purpose set forth.

5. In a button-setting machine, the combination, with a carrier and a die, of a channeled support carried by the die to receive one of a series of pins on the carrier, and an automatic switch for moving the carrier, substantially as and for the purpose set forth.

6. In a button-setting machine, the combination, with a carrier and a die, of a support fixed to the die and having the straight and 15 curved sides, and a spring-actuated switch located between the straight and curved portions, substantially as and for the purpose set forth.

7. In a button-setting machine, the combi-

nation of a standard provided with a fixed base, 20 a die working and guided in the base, a carrier hung upon the standard in line with the die, and having a series of pins on one side and a slotted flange projecting from the opposite side, a channeled support carried by the die and arranged in close proximity to the side of the carrier on which the pins are arranged, and an automatic switch on the support for acting on the pins, substantially as and for the purpose set forth.

25 In testimony that we claim the foregoing as our own we have hereto affixed our signatures in presence of two witnesses.

CHARLES E. TEMPLE.
